UNITED STATES PATENT OFFICE.

JOHN E. PACKARD, OF CHICAGO, ILLINOIS, ASSIGNOR TO MULTI-VENDING COMPANY, A CORPORATION OF SOUTH DAKOTA.

VENDING-MACHINE.

No. 823,633.

Specification of Letters Patent.

Patented June 19, 1906.

Application filed November 2, 1903. Serial No. 179,513.

To all whom it may concern:

Be it known that I, JOHN E. PACKARD, a citizen of the United States, residing at Chicago, in the county of Cook and State of Illinois, have invented a new and useful Vending-Machine, whereof the following is a specification.

My invention relates to that type of coin-controlled vending-machines wherein the goods to be sold are stored in a plurality of magazines in a movable goods-carrier and the purchaser shifts the said movable goods-carrier to bring into registry with the discharge mechanism the particular magazine from which he desires to procure goods; and my invention has for its object the providing of mechanism whereby the movement of the goods-carrier and the movement of the discharge devices may be effected independently, but not simultaneously, and also has for its object the effecting of all other improvements in operation or construction that may be found to obtain in the devices herein-after described or claimed.

In the accompanying drawings, forming a part of this specification, Figure 1 is a side elevation of the internal mechanism of the machine with the case in section and the central portion of the goods-carrier and adjacent case-wall broken away. Fig. 2 is a sectional plan view taken on the line 22 of Fig. 1. Fig. 3 is a front elevation of the entire machine with the internal mechanism indicated in dotted lines. Fig. 4 is a side and sectional view and detail of part of the coin-controlled mechanism for actuating the discharge device. Fig. 5 is a top plan view and detail of the same.

Like reference-numerals indicate like parts in all the figures.

10 is a rotary goods-carrier secured to the rotary shaft 11 and provided with a plurality of goods-magazines 12. A radially-slotted wheel 13 is rigidly attached to the lower part of said shaft and is rotated by means of the horizontally-oscillating hand-shaft 14, provided with the spring-pawl 15. Such horizontal oscillation of said hand-shaft is permitted by the pivot 16 and the horizontal slot 17 in the outer case of the machine. Said pawl is normally engaged in one of the slots 36 of said wheel when a goods-magazine is in proper registry with the discharge device; but when said hand-shaft is so moved

laterally a sufficient distance to shift the next goods-magazine into such discharge position the detent 21 is forced upward out of the socket 20 by the spring 35 into the aforesaid slot 36, and thereby so raises the pawl 15 against its weaker spring 37 that the hand-shaft 14 is free to be swung back to normal. Backward rotation of the goods-carrier from such new position is prevented by the ratchet and pawl 18 19 at the base of the shaft 11; but if the goods-carrier is not shifted sufficiently to allow the detent 21 to so raise the pawl 15 the carrier will merely move back with the hand-shaft when the latter is returned to normal. The reciprocating ejector 22, moving in the supports 23 24 and adapted to enter the apertures 25 in the base of the goods-carrier, discharges the goods-packages into the delivery-chute 26. The said ejector is reciprocated by the oscillating arm 27, projecting upward from the shaft 28. The section 29 of the coin-chute, whereof the upper section 30 is stationary, is rigidly secured to the shaft 28, and when a coin drops into said section 29 from said section 30 such coin presents its middle portion flatwise to the arm 31 of the vertically-oscillating hand-shaft 32 and forms such a connection between said arm 31 and the coin-chute section 29 that the raising of the hand-shaft 32 causes the backward movement of the said section 29, shaft 28, and arm 27, and consequent backward throw of the ejector 22. The spring 33 returns the arm 27 and ejector 22 to normal position. The vertical slot 34 in the outer case of the machine allows the upward movement of the handle of the hand-shaft 32, and the said shaft and handle return by their own weight to normal position. A dash-pot 38 prevents the abrupt recoil of the oscillating arm 27 under the action of the spring 33, and thereby both affords an opportunity for the release of the coin from the connector mechanism and also prevents injury to the machine. When the coin-chute section 29 is in normal position, the coin is retained therein by the arm 39 of the three-armed spider 40, that is pivoted on the standard 41, projecting from the back of said coin-chute section. When said coin-chute section is rocked back, the arm 42 of said spider comes in contact with the fixed stop 43 and causes the arm 39 to be moved out of the path of the coin, leaving the coin free to fall out of the chute as

soon as released by the arm 31 of the hand-shaft 32, and to effect such release the chute-section 29 is momentarily detained at the backward limit of its throw by the spring-5 catch 44, which is again disengaged, when the hand-shaft arm 31 returns to normal position, such disengagement being effected by the contact of the stud-pin 45 with the hooked rod 46, that is pivotally attached to the 10 lower arm of the spring-catch 44. The arm 39 of the three-armed spider 40 is returned to normal position by the spring 47, attached to the arm 48 of said spider.

The machine is provided with a suitable 15 case 49, having a locked lid 50.

It is obvious that the movement of the goods-carrier and the movement of the discharge mechanism both being effected by the same handle, but by different operations thereof, 20 cannot be effected simultaneously, but must be effected in alternation with each other, and that the two movements cannot be brought into interference with each other, so as to in any manner balk or injure the machine, and 25 it is further obvious that the delivery mechanism may be actuated any desired number of times without shifting the goods-carrier, so that an indefinite number of articles may be purchased successively from one and the 30 same goods-magazine, or the goods-carrier may be shifted a sufficient extent to bring either the next or any other one of the goods-magazines into registry with the discharge mechanism that the operator may make his 35 purchase from any desired one of the plurality of goods-magazines on the goods-carrier.

To shift the goods-carrier, the operator simply grasps the handle 14 and swings it to the left to the end of the horizontal slot 17, 40 which effects a sufficient rotation of the carrier to bring the next goods-magazine into registry with the delivery mechanism. When the handle has so reached the left-hand limit of its movement, the spring-pawl 15 is automatically forced out of engagement with the disk 13 by the spring-detent 21, and by engaging in the slot out of which the said pawl has been so raised the said detent 21 tends to retain the said disk 13 into the new position 45 to which said disk has been shifted. The handle 14 may now be returned by the operator to the right-hand end of the slot 17 without moving the goods-carrier, and when the handle reaches the said right-hand end of the 50 said slot the spring-pawl 15 will engage another slot 36 in the disk 13, and by swinging the handle to the left-hand end of the slot 17 another shifting of the goods-carrier may be effected, as before. This operation may be 55 repeated until the desired goods-magazine is in registry with the discharge mechanism.

To effect the delivery of an article, a coin is dropped into the coin-chute 30 and takes the position shown in Fig. 4. Thereupon the 60 mere raising of the handle 14 to the top of

the vertical slot 34 effects the ejection of an article from the goods-magazine that then happens to be in registry with the ejector 22. This operation may be repeated as frequently as a coin is dropped into the coin-chute and 70 is entirely independent of the shifting of the goods-carrier, although the operator uses the same handle that is used in effecting the rotation of the goods-carrier.

My invention is hereinabove set forth as 75 embodied in one particular form of construction; but the invention is not limited to such particular form or to less than all the possible forms in which the subject-matter of the following claims may be embodied.

I claim—

1. In a vending-machine, in combination, a movable goods-carrier mechanism, an independently-movable delivery mechanism co-operating therewith, a coin-controlled device 85 controlling only one of said mechanisms, a single operating member whereby each of said mechanisms may be repeatedly operated independently of the other, and separate means for connecting said member with said mechanisms respectively, substantially as 90 specified.

2. In a vending-machine, in combination, a pivotally-movable goods-carrier mechanism, an independently - movable delivery 95 mechanism co-operating therewith, a coin-controlled device controlling only one of said mechanisms, a single operating member whereby each of said mechanisms may be repeatedly operated independently of the other, and separate means for connecting said member with said mechanisms respectively, substantially as 100 specified.

3. In a vending-machine, in combination, a rotary goods-carrier mechanism, an independently-movable delivery mechanism co-operating therewith, a coin-controlled device 105 controlling only one of said mechanisms, a single operating member whereby each of said mechanisms may be repeatedly operated independently of the other, and separate means for connecting said member with said mechanisms respectively, substantially as 110 specified.

4. In a vending-machine, in combination, 115 a movable goods-carrier mechanism, an independently-movable and coin-controlled delivery mechanism co-operating therewith, a single operating member whereby each of said mechanisms may be repeatedly operated independently of the other, and separate means for connecting said member with said mechanisms respectively, substantially as 120 specified.

5. In a vending-machine, in combination, 125 a pivotally-movable goods-carrier mechanism, an independently-movable and coin-controlled delivery mechanism co-operating therewith, a single operating member whereby each of said mechanisms may be repeatedly 130

operated independently of the other, and separate means for connecting said member with said mechanisms respectively, substantially as specified.

5 6. In a vending-machine, in combination, a rotary goods-carrier mechanism, an independently-movable and coin-controlled delivery mechanism coöperating therewith, a single operating member whereby each of 10 said mechanisms may be repeatedly operated independently of the other, and separate means for connecting said member with said mechanisms respectively, substantially as specified.

15 7. In a vending-machine, in combination, a hand-operated movable goods-carrier mechanism, an independently-movable hand-operated delivery mechanism coöperating therewith, a coin-controlled device controlling only 20 one of said mechanisms, a single operating member whereby each of said mechanisms may be repeatedly operated independently of the other and whereby one of the mechanisms is hand-operated as aforesaid, and separate 25 means for connecting said member with said mechanisms respectively, substantially as specified.

8. In a vending-machine, in combination, a hand-operated pivotally-movable goods-30 carrier mechanism, an independently-movable delivery mechanism coöperating therewith, a coin-controlled device controlling only one of said mechanisms, a single operating member whereby each of said mechanisms 35 may be repeatedly operated independently of the other and whereby one of the mechanisms is hand-operated as aforesaid, and separate means for connecting said member with said mechanisms respectively, substantially 40 as specified.

9. In a vending-machine, in combination, a hand-operated rotary goods-carrier mechanism, an independently-movable delivery mechanism coöperating therewith, a coin-controlled device controlling only one of said mechanisms, a single operating member whereby each of said mechanisms may be repeatedly operated independently of the other and whereby one of the mechanisms is hand-45 operated as aforesaid, and separate means for connecting said member with said mechanisms respectively, substantially as specified.

10. In a vending-machine, in combination, 55 a hand-operated movable goods-carrier mechanism, an independently-movable hand-operated and coin-controlled delivery mechanism coöperating therewith, a single operating member whereby each of said mechanisms 60 may be repeatedly operated independently of the other and whereby one of the mechanisms is hand-operated as aforesaid, and separate means for connecting said member with said mechanisms respectively, substantially 65 as specified.

11. In a vending-machine, in combination, a hand-operated pivotally-movable goods-carrier mechanism, an independently-movable hand-operated and coin-controlled delivery mechanism coöperating therewith, a single operating member whereby each of 70 said mechanisms may be repeatedly operated independently of the other and whereby one of the mechanisms is hand-operated as aforesaid, and separate means for connecting said member with said mechanisms respectively, substantially as specified. 75

12. In a vending-machine, in combination, a hand-operated rotary goods-carrier mechanism, an independently-movable hand-operated and coin-controlled delivery mechanism coöperating therewith, a single operating member whereby each of said mechanisms may be repeatedly operated independently of the other and whereby one of the mechanisms is hand-operated as aforesaid, and separate 80 means for connecting said member with said mechanisms respectively, substantially as specified. 85

13. In a vending-machine, in combination, a movable goods-carrier mechanism, an independently-movable delivery mechanism coöperating therewith, a coin-controlled device controlling only one of said mechanisms, a hand-actuated operating member whereby 90 each of said mechanisms may be repeatedly operated independently of the other, and separate means for connecting said member with said mechanisms respectively, substantially 95 as specified. 100

14. In a vending-machine, in combination, a pivotally-movable goods-carrier mechanism, an independently-movable delivery mechanism coöperating therewith, a coin-controlled device controlling only one of said mechanisms, a hand-actuated operating member whereby each of said mechanisms may be repeatedly operated independently of the other, and separate means for connecting said member with said mechanisms respectively, 105 substantially as specified. 110

15. In a vending-machine, in combination, a rotary goods-carrier mechanism, an independently-movable delivery mechanism coöperating therewith, a coin-controlled device controlling only one of said mechanisms, a hand-actuated operating member whereby each of said mechanisms may be repeatedly operated independently of the other, and separate means for connecting said member with said mechanisms respectively, 115 substantially as specified.

16. In a vending-machine, in combination, a movable goods-carrier mechanism, an independently-movable delivery mechanism coöperating therewith, a coin-controlled device controlling only one of said mechanisms, a single operating device whereby each of said mechanisms may be repeatedly operated independently of the other, and means 125 130

whereby a goods-magazine is automatically brought into proper registry with the goods-ejector before a movement of the delivery mechanism can be effected by the operator, substantially as specified.

- 5 17. In a vending-machine, in combination, a movable goods-carrier mechanism, an independently-movable delivery mechanism coöperating therewith, a handle adapted to
10 move both mechanisms, the one in alternation with the other, and automatic means whereby said goods-carrier is disengaged from said handle at the limit of a movement sufficient to bring a new goods-magazine into
15 registry with the discharge mechanism but is returned with the return movement of said handle if the forward movement of the latter has been less than sufficient to so bring a new goods-magazine into registry with the discharge mechanism, substantially as specified.

18. In a vending-machine, in combination, a discharge device, a movable coin-chute section, an independent hand-operated arm for moving said chute-section, a mechanism adapted to retain a coin in said chute-section, 25 and in front of said arm, when said section is in normal position and to release said coin when said chute-section has been rocked back by said arm, a catch for momentarily detaining said chute-section in the latter position, 30 and a trip adapted to release said catch as the aforesaid arm returns to normal position, substantially as specified.

In testimony whereof I have hereunto set my hand in the presence of two subscribing 35 witnesses.

JOHN E. PACKARD.
